DESIGN FOR A BOTTLE

William J. Latchford, Jr., Los Angeles, Calif., assignor to Bohemian Distributing Co. Ltd., Los Angeles, Calif., a corporation of California

Application January 26, 1934, Serial No. 50,521

Term of patent 14 years

To all whom it may concern:

Be it known that I, WILLIAM J. LATCHFORD, Jr., residing at Los Angeles, in the county of Los Angeles and State of California, have invented a new, original, and ornamental Design for a Bottle, of which the following is a specification, reference being had to the accompanying drawing, forming part thereof.

In the drawing:

I claim:

The ornamental design for a bottle, substantially as shown and described.

WILLIAM J. LATCHFORD, JR.
